THERMIONIC POWER AMPLIFIER FOR DELIVERING HIGH POWER TO LOW IMPEDANCE LOADS

Bertram Morton Hadfield, Harrow Weald, England, assignor to Automatic Electric Laboratories Inc., Chicago, Ill., a corporation of Delaware

Application October 29, 1945, Serial No. 625,367
In Great Britain December 15, 1944

3 Claims. (Cl. 179—171)

1

The present invention relates to thermionic valve circuits and is more particularly concerned with circuits employed for feeding power into an output load.

One of the objects of the invention is to provide a circuit arrangement employing a pentode or beam tetrode valve of conventional design which is operated at a given steady anode voltage or from a steady anode voltage supply, the arrangement being such that a power output greater than normal is obtained in an anode load substantially lower than normal.

A further object of the invention is to provide a circuit arrangement employing a pentode or beam tetrode valve as a power output valve with an anode load impedance having a value which is small compared with the value necessary in a conventional circuit.

According to one feature of the invention, in a thermionic valve circuit employed for feeding power into an output load and including one or more thermionic valves of the pentode or beam tetrode type, having at least one additional grid electrode between the control grid and the anode, the steady, positive voltage applied between the additional electrode and the cathode is at least twice that of the steady, positive voltage applied between the anode and cathode.

According to a further feature of the invention, the ratio of the steady, positive voltage applied between the additional electrode and the cathode to the steady, positive voltage applied between the anode and the cathode has a value which is greater than unity and which is determined by the value of the anode load impedance.

In modern communication engineering, the use of higher carrier frequencies over transmission media of increasing attenuation and of lower characteristic impedance requires that the amplifiers or repeaters deliver high energy levels into low impedances. While higher energy levels can be obtained by using higher amplifier supply voltages and lower impedances can be matched to the output stage by higher ratio output transformers in theory, neither of these solutions is satisfactory in practice because the normal high current anode supply voltage may be approximately 130 volts and the poorer high frequency response of high ratio transformers limits the overall performance of the system. Furthermore the application of voltage and current negative feedback to the amplifier to stabilise its gain and internal impedance at desired values becomes more difficult, owing to the increased residuals of the feedback network if the latter is made of

5 stages, will the more adversely affect the overall frequency characteristics if higher anode load impedances are used, while the unwanted feedback from anode to grid in the output stage, due to anode-grid capacitance, is the more effective as the gain of the stage increases.

In order to meet these requirements, it has been proposed to employ thermionic valves specially designed to pass high currents at low anode supply voltages. The application of the invention to such a communication system, however, enables pentode or beam tetrodes of conventional design to be employed, the only condition being that a low-current voltage supply is made available for the screen of a higher value than that available for the anode.

The invention will be better understood from the following description taken in conjunction with the accompanying drawings in which:

Fig. 1 shows some curves used to illustrate the principles of the invention while

Fig. 2 shows, by way of example, a circuit arrangement embodying the invention.

The general design theory for the operation of thermionic valves under conditions such that the limiting values of voltage and current are always just attained has been discussed in the "Wireless Engineer," vol. 21, August 1944, pages 368 to 376. It is shown that, assuming the minimum anode current I_b is negligible compared to the maximum anode current I_a , the anode output volt-amperes is given by

$$p.k.V \frac{(N+1)}{N} \cdot I_a \quad (1)$$

and the anode volt-ampere efficiency is given by

$$p.k.(M+1) \cdot \frac{(N+1)}{N} \quad (2)$$

where

p = the ratio of the anode load voltage to the anode-cathode D. C. voltage drop (V) across the valve.

k = a constant depending on the input waveform.

N = the ratio of the voltage excursions from a given operating point, and

M = the ratio of the current excursions from the same operating point.

3

Also it can be shown that the anode load resistance is given by

$$R = \frac{(V_b - V_a)}{(I_a - I_b)} = \frac{p \cdot V \cdot (N+1)}{I_a \cdot N} \quad (3)$$

where V_b and V_a are respectively the maximum and minimum anode voltages.

It can also be shown that for a pentode or beam tetrode valve, the anode current is related to the screen voltage E_s in the following manner:

$$I_a = \frac{K_a}{\mu^m} (E_s - \mu E_g)^m \quad (4)$$

where

μ =the grid-screen amplification factor

K_a =a constant depending on the type of valve

E_g =a given control grid voltage and

m =a positive number.

Further, if E_g is written as

$$\frac{s \cdot E_s}{\mu}$$

where s is a positive number if positive, maximum grid-cathode voltage is used and vice versa, and E_s =screen-cathode voltage, (4) now becomes

$$I_a = \frac{K_a}{\mu^m} (E_s)^m (1+s)^m \quad (5)$$

It should be noted that this definition of the maximum grid-cathode voltage is in terms of the negative grid-cathode voltage

$$\frac{E_s}{\mu}$$

which will produce substantially zero anode current. For normal non-grid current operation, s is zero and for grid current operation s is positive. The value assigned to s will depend on the nature of the input waveform and the desired bias condition. For instance for a waveform having equal positive and negative amplitudes and for grid current operation with zero bias, s is +1.

Further it can be shown that the greatest output for a pentode or beam tetrode (other things being equal) is obtained when the minimum anode voltage swing V_a is made to coincide with the "knee" of the anode characteristic, and assuming this to occur at q times the screen voltage E_s , then

$$(1-p)V = q \cdot E_s \quad (6)$$

Hence Equation 5 above becomes,

$$I_a = \frac{K_a}{\mu^m} \left(\frac{(1-p)V}{q} \right)^m (1+s)^m \quad (7)$$

Substitution of Equation 7 above in Equations 1 and 3 above gives the following,

Anode output volt-amperes=

$$k \cdot p \cdot \frac{(1-p)^m}{q^m} \frac{(N+1)}{N} (1+s)^m V^{m+1} \cdot \frac{K_a}{\mu^m} \quad (8)$$

Anode load resistance, R =

$$\frac{p}{(1-p)^m} \frac{(N+1)}{N} \frac{q^m}{V^{m-1}} \frac{1}{(1+s)^m} \cdot \frac{\mu^m}{K_a} \quad (9)$$

Considering Equation 8 above, it is clear that for a given valve, i. e.

$$\frac{\mu^m}{K_a}$$

anode-cathode voltage (V), grid excitation (s), peak voltage swing ratio (N), waveform (k), and since the value of q is substantially the same for all pentode or beam tetrode valves, then the

4

maximum anode output is obtained when $p(1-p)^m$ is a maximum, i. e. by differentiation, when

$$p = \frac{1}{1+m}$$

Taking m as 1.5 as being a well accepted figure over the normal range of anode currents, then $p=0.4$ gives the maximum anode output. Taking q as 0.2 (from inspection of characteristics of normal pentode and beam tetrode valves), it will be seen from Equation 6 above that the normal value of p which is used when $E_s=V$, is 0.8. From Equations 6, 8 and 9 above it can now be

15 seen that (other factors remaining constant),

(a) The anode output is 2.63 times as great if $p=0.4$ instead of 0.8,

(b) The anode load resistance is 0.096 times the normal value, and

20 (c) The p value of 0.4 means that

$$\frac{E_s}{V} = 3$$

Before proceeding further to demonstrate the effects of using p values around 0.4, it is pointed out that for a resistance anode load (i. e. no choke or transformer) a maximum anode output for a given anode busbar voltage (V_b) and for all other factors constant except p , is also obtained when E_s is three times V_b . This can be found by substituting

$$V_b = \left(1 + \frac{p}{N} \right) V$$

35 in Equation 8 above, differentiating the resulting p function for a maximum, and substituting the p value obtained in Equation 6 above. This case is, however, of rare occurrence in practice, since 40 clearly the maximum output will be smaller than for the choke or transformer coupled load.

Taking the choke or transformer coupled load case as being the more profitable (i. e. where the steady anode-cathode voltage V is substantially equal to the anode busbar voltage), the effects of using p values around 0.4 will now be described in order that the application of the invention may be appreciated.

In order to put the description in terms of practical figures, the following will be assumed. Operation to a sinusoidal input is usual and gives N and M equal to unity, while k has the value 0.125; it is assumed that the output is also sinusoidal by the use of sufficient negative feedback to the prior amplifying stages. The real assumption at this stage is that M and N are 1; the waveform of the output is immaterial to this discussion and the assumed value of k must be altered in accordance with the actual waveform; the assumption that k is 0.125 for a sinusoidal input is no more erroneous than the assumption that the corresponding output is also sinusoidal. As is normal, grid current operation will not be assumed, so that s is 0, while as stated before a value for q of 0.2 will be taken as representative of normal pentode or beam tetrode valves. The exponent m will be taken as 1.5, and the steady anode-cathode voltage as 100 volts. The latter assumption permits operation from the normal 130 volt supply with enough allowance for the steady voltage drop on the anode choke or transformer, and for automatic grid bias if required. The value of the valve factor

$$\frac{\mu^m}{K_a}$$

of 0.32. The grid bias will be approximately one-half the negative grid base of the valves, i. e.

$$\frac{E_s}{2}$$

and if μ be assumed to be 10, then the grid bias will be 17 volts; in practice this value should be varied in situ until equal incipient overloading on both positive and negative peaks of the input waveform is obtained, because the bias should be such as to give a steady anode current one-half the maximum; otherwise the calculated output of 10 watts will not be given.

Fig. 2 shows a circuit diagram of this amplifier, with the basic values of the output stage shown in figures. The input is applied from terminals A, B, to the input transformer T₁ of assumed step-up ratio 5:1, the secondary voltage being applied via a grid resistance R₇ to the grid of the first stage valve V₁ and ground. The valve V₁ is a pentode or beam tetrode having an anode impedance comprised by resistance R₅ and inductance L₁ in order to obtain a maximum of response at high frequencies, and the alternating voltage thereon is fed to the output stage via condenser C₁ and resistance R₈, over a grid resistance R₉ to the grid and via the grid bias potential of approximately -17 volts to the cathode. The four paralleled output valves V₂, V₃, V₄ and V₅, have their screen grids commoned and taken to +340 volts, their cathodes commoned and taken to ground, and their anodes commoned via individual oscillation-stopper resistances R₁₀, R₁₁, R₁₂ and R₁₃, of the order of 10 ohms each, to the anode choke L₂ designed to carry the steady anode current of 625 mA., and the small alternating component due to its inductance. The output is taken from the anode and cathode via the large condenser C₂ to the output transformer T₂ of unity ratio and the feedback network and on via the secondary winding of T₂ to the load resistance L of 50 ohms. The series current feedback resistance R₃ of 2.5 ohms is connected in series with the primary of T₂, while the shunt feedback ratio of 0.05 is provided by resistances R₂ and R₁. As the sum of the voltages on R₂ and R₃ must be fed into the cathode circuit of V₁ for negative feedback, R₂ is made of convenient value to provide the necessary steady grid bias voltage for V₁, say 300 ohms, when R₁ becomes 5,700 ohms. The loss on the shunt feedback path is therefore less than one-hundredth of the wanted output, say 0.1 watt and is negligible. In order to prevent local feedback on V₁, the screen is decoupled to its cathode by condenser C₃ and a series anode resistance R₆, which must be approximately 3000 ohms in order not to reduce unduly the value of R₂ and R₃. The positive busbar supply for the amplifier, other than that required for the output stage screens, has been shown at the conventional value of 130 volts, and allows 30 volts steady drop on the anode choke L₂, i. e. a D. C. resistance of 48 ohms.

The provision of the higher voltage, low current, screen voltage supply for the output stage necessary for carrying out the invention may be made from the existing battery supplies by well known means such as a rotary converter, or a vibrator unit, operated from the 130 volt or 24 volt batteries. Such means are readily available since they are required normally for the operation of radio receivers which use the conventional types of valves at around screen volt-

ages of 300 volts, where a main supply is not available, or alternatively, not reliable.

The invention has been confirmed experimentally by applying a steady anode-cathode voltage of 100 to a valve such as the 6L6G, and three successive screen-cathode voltages of 100, 200 and 300. At each of the screen voltages the maximum resistance anode load was found by inspection of the output waveform, that resistance which just gave perceptible flattening of the positive and negative anode voltage swings being the correct one for a grid input just attaining anode current cut off and grid current. The three anode load resistances resulting were found to be in the ratio of 1:0.25:0.1 and occurred with peak voltage swings 0.8, 0.6 and 0.4 of the steady anode-cathode voltage, for screen voltages in the ratios of 100:200:300 respectively. The invention has also been used in an application where the operation of low resistance anode loads at high energy levels is a well known difficulty. This occurs in the design of test oscillators covering a very wide frequency range. In this application it was required to generate an output of 6 watts in an anode resistance load of 600 ohms over a frequency range of 60 cycles/sec. to 1.5 megacycles/sec.; a range which practically precluded the use of an output transformer but enabled the use of a choke. By using steady anode-cathode and screen-cathode voltages of 150 and 300 respectively, these requirements were satisfied with a single valve of the KT66 type.

I claim:

1. In a power amplifier comprising a vacuum tube, a cathode, a control grid, a screen grid and a plate in said tube, means in said tube for suppressing secondary electron emission between said plate and said screen grid, a source of direct current plate potential and a plate impedance connected in series between said plate and said cathode for applying a positive direct current potential to said plate, an output load circuit connected between said plate and said cathode, the impedance of said load circuit being substantially less than the impedance conventionally used with said tube for delivering maximum power output at plate potentials and screen grid potentials that are approximately equal, means for applying an input signal potential between said control grid and said cathode to produce a signal current in said output circuit, a source of direct current screen grid potential, means for applying said screen grid potential to said screen grid, the screen grid potential being substantially greater than the plate potential, the tube having positive internal impedance at all times, the ratio of the screen grid potential to the plate potential being determined by the value of the load circuit impedance so as to cause maximum power to be delivered thereto, said output circuit having an impedance as low as approximately one-tenth of said conventional output impedance.

2. In a power amplifier as claimed in claim 1, a similar tube in parallel with said first tube, the anode, cathode, screen grid and control grid of said similar tube commoned to the anode, cathode, screen grid and control grid, respectively, of said first tube.

3. The combination of a power amplifier as claimed in claim 1 with a voltage amplifier, a tube in said voltage amplifier having at least a cathode, a control grid, and a plate, the control grid of said power amplifier coupled to the plate of said voltage amplifier, means for applying 75 positive potential to the plate of said voltage

5

will be taken as 20,000, since it is found that a wide variety of normal valves give this order, for instance the following series: KT66, EL50, 6L6G and RCA807.

With these assumptions we have,

$$\text{Anode output watts} = 14.9(1-p)^{1.5} \quad (10)$$

$$\text{Anode load resistance, } R = 358 \cdot \frac{p}{(1-p)^{1.5}} \text{ ohms} \quad (11)$$

and Fig. 1 shows curves for these two quantities plotted on a logarithmic scale against values of p from 0 to 1 on a linear scale. By so plotting, the effects of varying the assumed value of any of the constants may be seen at a glance, by shifting the curves bodily by an amount corresponding to the ratio of the variation. For instance, reduction of the valve factor

$$\frac{\mu^m}{K_a}$$

by 0.5 times will shift the R curve down, and the ω curve up, by the distance between 1 and 2 on the vertical scale; in passing it may be noted that such a change represents about the maximum possible in these directions with present valves. The ratio $E_s:V$ corresponding to the p values has also been given.

It will be seen that over a range of from 2 to 4 (between dotted lines 1 and 2) for

$$\frac{E_s}{V}$$

about twice the anode watts are obtainable for a range of 10:1 in anode load resistance, and the geometric mean of this resistance range is at least one-tenth the normal value with

$$\frac{E_s}{V}$$

of unity (i. e. a p value of 0.8). It will also be seen that the order of resistance approaches more nearly that required for modern transmission media. For example, an output of 10 watts may be required for carrier operation on a submarine cable of impedance 50 ohms. This could be met with four valves of the present type (or two having

$$\frac{\mu^{1.5}}{K_a}$$

of 10,000) by operating them at a p value of 0.32 (i. e. with $E_s=3.4V$), since the single valve output and resistance are 2.5 watts and 200 ohms respectively, and with an output transformer ratio of unity.

In general it will be seen that a wide range of anode load resistance is available for substantially the same output, by means of the invention, in that a proper choice of the ratio

$$\frac{E_s}{V}$$

will provide the means for meeting any specific case.

From the general Equations 8 and 9 above, while it is possible considerably to raise the output by increasing V above the assumed value of 100 volts, it is not possible to produce a large reduction in R , since the former is proportional to the 2.5 power of V and the latter to the 0.5 power of V . Moreover there is a large choice of output pentodes or beam tetrodes whose maximum permissible screen voltage lies between 300 and 400 volts all of which can be used with the

invention if a steady anode voltage of 100 is adhered to.

The invention also ameliorates the position as regards the provision of voltage and current feedback circuits without unduly affecting the output or circuit design. In the case of the voltage feedback ratio, clearly the same resistance potentiometer across the anode load will have about one-tenth the effect at

$$\frac{E_s}{V}$$

ratios around three, since the anode load resistance required is one-tenth; that is, the watts lost in this potentiometer will be one-tenth. Alternatively if the normal potentiometer gives difficulty with residuals because of its high impedance, the latter can be reduced without much additional loss. As regards the current feedback resistance, difficulty is often experienced where anode chokes are not desired in that it must then be placed in series with the anode transformer primary winding and occasions a marked loss in steady anode voltage. Now the value of the current feedback resistance is proportional to the anode load resistance, for a given voltage feedback ratio and a given ratio of load to internal impedance. From Equation 7 above, the steady anode current will be proportional to $(1-p)^m$ (since the steady current is proportional to the maximum), while from Equation 9 above the anode load resistance (and hence the current feedback resistance) is proportional to $p/(1-p)^m$. Hence the product of these is proportional to p , so that reduction of p value will reduce the steady voltage drop on the current feedback resistance in direct proportion. The incorporation of the current feedback resistance in the output stage without the use of a choke is therefore facilitated by the invention.

By way of example, and in order to show the application of the invention, the basic design of the output stage of the amplifier previously cited will now be undertaken. Assuming that a stabilised gain of 34 db is required, and as the output transformer ratio may be unity if four valves in parallel are used at a p value of 0.32, then 14 db can be obtained on the input transformer of ratio 1:5 step-up. This leaves 20 db to be obtained from the amplifier, and the use of one stage prior to the output will enable sufficient open-circuit gain to be obtained, so that gain stability will be high and the feedback network may be calculated from the usual simplified formulae. On this basis the voltage feedback ratio required will be

$$\frac{1}{2.10}$$

or 0.05 (the 2 is for the case of an internal impedance equal to the load), while the current feedback resistance will be 0.05 times the anode load of 50 ohms, i. e. 2.5 ohms. The steady anode current of the four paralleled output valves will be one-half the maximum I_a , and can be calculated from Equation 7 above using a p value of 0.32, $V=100$ volts, $q=0.2$, $s=0$,

$$\frac{m}{K_a} = 20,000$$

and $m=1.5$ as before. A value of 625 mA. is obtained. The steady screen voltage required will be 340, from Equation 6 above and a p value

amplifier from said source of plate potential, means for applying the negative potential of said last source to the grid of said voltage amplifier, a feed-back circuit including three resistors connected in series, the first and second ones of said resistors connected in parallel with said output circuit, the third one of said resistors connected between said output circuit and the negative pole of said plate potential source, the cathode of said voltage amplifier connected to the junction point of said first and second resistors, the resistors of said feed-back circuit of such resistance that the normal grid-to-cathode direct-current voltage bias for the tube of said voltage amplifier and the required feed-back signal voltage are developed between said last cathode and the negative pole of said source of plate potential.
